(57) **CLAIM**

The ornamental design for an atomizer for electronic cigarette, as shown and described.

DESCRIPTION

FIG. 1 is a top perspective view of an atomizer for electronic cigarette, showing our design;

FIG. 2 is a bottom perspective view thereof;

FIG. 3 is a front plan view thereof;

FIG. 4 is a rear plan view thereof;

FIG. 5 is a left side elevation view thereof;

FIG. 6 is a right side elevation view thereof;

FIG. 7 is a top side view thereof; and,

FIG. 8 is a bottom side view thereof.

The broken lines depict portions of the atomizer for electronic cigarette that form no part of the claimed design.
